UNITED STATES PATENT OFFICE.

JULES COURNAND, OF PARIS, FRANCE.

SYRINGE WITH PROGRESSIVELY-GRADUATED AUTOMATIC ACTION.

1,416,614.

Specification of Letters Patent. Patented May 16, 1922.

Application filed November 28, 1913. Serial No. 803,556.

(GRANTED UNDER THE PROVISIONS OF THE ACT OF MARCH 3, 1921, 41 STAT. L. 1313.)

To all whom it may concern:

Be it known that JULES COURNAND, citizen of the French Republic, residing at 28 Avenue de l'Opera, Paris, France, has invented certain new and useful Improvements 5 in Syringes with Progressively-Graduated Automatic Action, of which the following is a specification.

This invention relates to a syringe that has 10 a piston which is operated by a mechanical device and by means of which a progressive quantity of an anesthetic liquid for example can be injected at the desired place and at the required moment. This improved 15 syringe can be used in any case of hypodermic injection and particularly in dental operations.

For dental operations as carried out at 20 the present time a hypodermic injection is effected in two stages, the first comprising the introduction and placing of the needle, the second the injection of the whole or a portion of the contents of the syringe.

For the first phase the barrel of the syringe 25 is conveniently held like a pencil, between the thumb, the fore-finger and the middle finger.

For the second phase the body of the 30 syringe is held like a cigar, between the middle finger and the fore-finger which are placed on the two grips arranged at the end of the barrel of the syringe, in order to enable a thumb placed on the piston rod and acting thereon to apply pressure.

35 The changes of position effected by the fingers in order to pass from the first to the second stage are frequently attended with difficulty, because the patient may move and the incommode operator cannot perform 40 that operation as precisely and delicately as required, particularly in the case of diploic and regional punctures, and when the needle is mounted on a bent rod, a rod that is rendered necessary for reaching a 45 part of the buccal cavity that is not easily accessible, or is inaccessible with a straight needle. Consequently the needle may come out of the tissues or break in them.

In the second phase the syringe is not 50 well placed for effecting a long pressure and at the same time for following the instinctive resistant movements of the patient.

The resistance presented by the tissues to 55 the penetration of the injected liquid, sometimes necessitates a powerful action of the thumb, nay even of the palm of the hand,

and it is not infrequently observed that there is a sudden relaxation of the resistance, indicating a laceration of the tissues by the powerful pressure of the liquid, giving rise 60 to traumatic accidents which are painful and serious. But independently of these traumatic accidents there is reason for fearing accidents of a toxic kind in consequence of the diffusion over a large surface owing to 65 the sudden irruption into the circulating stream of a large quantity of anesthetic whereas it ought to be injected into a very circumscribed space, and very gently that is to say progressively so as to proportion 70 the quantity of the anesthetic to the susceptibility of the patient. Finally a sudden inrush of liquid under powerful pressure causes intolerable pain owing to the fact that the tissues are already excessively dis- 75 tended through the inflammation.

Injections into the diploë and punctures for regional anesthesia necessitate that the syringe be accurately positioned.

These practical necessities show the advantage:-

1st. Of holding the syringe in the position for the first stage so as to be always ready to follow the patient in his instinctive resistant movements, because in that position the 85 syringe is well in hand.

2nd. Of injecting the liquid very slowly and progressively proportionally to the susceptibility of the patient in order to prevent the liquid from being suddenly diffused 90 in the tissues.

The syringe with automatic progressive action that constitutes the present invention ensures these advantages.

Fig. 1 is a longitudinal sectional view of 95 the device;

Fig. 2 is a longitudinal sectional view of a portion of the device taken on the plane indicated by the line 2-2 of Fig. 1;

Figs. 3 and 4 are transverse sectional 100 views taken on the planes indicated respectively by the lines 3-3 and 4-4 of Fig. 1;

Fig. 5 is an end view of the device with the flexible member disconnected from the sleeve and the latter revolved through 90° 105 from the position it is shown in in Figs. 1 to 4;

Fig. 6 is a side elevation of the end of the flexible member;

Fig. 7 is a perspective view of one end 110 of the shaft upon which the worm is mounted; and

Fig. 8 is a similar view of one end of the hub which fits upon the shaft shown in Fig. 7.

The cylindrical body or barrel 1 of the syringe which is of the usual form is provided with an external nipple 2, through which the needle 3 which may be either straight or bent runs. This needle is secured tightly and firmly by means of the cap 4 screwed on to this nipple.

In this body 1 the piston is moved automatically and very slowly and forces into the needle 3 the anesthetic or other liquid contained in the body 1, and which is to be injected into the tissues.

Onto the body 1 opposite the nipple 2 a small box 5 is screwed which contains the mechanism for operating the piston-rod 6 of the syringe. The box 5 extends transversely 20 of the body or barrel 1.

This mechanism consists of a worm 7 fixed on a shaft 8 that projects from the box 5 and a helicoidal or worm wheel 9 with a hub 10 that is screw-threaded to suit the pitch of the screw-thread of the piston-rod 6. The wheel 9 with its hub 10 constitutes a nut. The external cylindrical side of this hub is held in the box 5 concentrically to the axis of the rod 6 by means of two discs 11 and 12 25 attached one to the bottom of the box 5, the other to the interior surface of its cover 13. On to this cover a sleeve 15 is fixed by means of screws 14. The sleeve has an end closure 16 in which an opening is drilled which is 30 partially circular at 17 and partially rectilineal at 18 opposite flat parts 19 of the piston-rod 6 which runs freely through it. This opening acts as a guide for the rod, and prevents it from turning. Beyond the closure 35 16 the piston-rod is furnished with a milled nut 20 fastened on to it.

The piston-rod is screw-threaded over the greater part of its length and it is screwed into the screw hub 10 of the helicoidal wheel 45 9, a part of the screw-threaded portion being removed through two parallel flat surfaces formed on this rod. The flat surfaces 19 which surmount the screw-threaded part 6 are graduated for the purpose of ascertaining 50 the extent to which the rod is pushed into the cylindrical body 1. To the cylindrical end 21 of the rod a piston 22, for example metallic, is attached, which has one or two peripheral grooves 23 as may be required. The cylindrical nipple 21 is lodged 55 freely in the corresponding hollow of the piston 22 and a pin 24 connects this nipple with the piston 22. This non-rigid arrangement of the piston on its rod is intended to 60 enable the piston to move to a slight extent in the cylindrical body 1 so as to prevent the wedging of the piston against the inside of the body 1 which might happen in consequence of the slight play existing 65 between the gearings 7 and 9.

One of the novel features of this syringe provided with a mechanically operated piston consists in the arrangement whereby the shaft 8 of the worm 7 is disposed at right angles to the longitudinal axis of the syringe 70 and situated at a distance from that axis equal to the sum of the radii of the pitch diameters of the worm 7 and wheel 9. The flexible device A has a swiveled connection with the box 5 so that its rotary shaft which 75 is disposed at right angles to the shaft 8 may be kept in parallel relation to the longitudinal axis of the syringe.

This arrangement is very important for during use the syringe is held between the 80 middle finger and the fore-finger and the fore-finger placed at the height of the box 5 on its projecting surfaces, so that the flexible device A containing the rotary shaft of the electric motor for example, connected firmly with the shaft 8 that controls the syringe mechanism, partially supports this syringe and thus relieves the operator's hand, which is in no way incommoded by the flexible shaft, whilst it moves the syringe 90 in any direction. Furthermore the hand does not impede the rotary shaft of the flexible device.

The firm though easily removable connection between the end of the rotary shaft 95 of the flexible device A and the operating shaft 8 is effected in the following manner: One end of the shaft 8 projects from one side of the box 5 and is provided adjacent this side of the box 5 with a disk 27. The 100 projecting end of the shaft 8 extends through a sleeve 25 and a terminal piece or collar 26 fixed thereto. The terminal piece or collar 26 is enlarged at one end to provide it with an internal shoulder. The 105 disk 27 is disposed within the enlarged portion of the terminal piece or collar 26, and is confined between the internal shoulder of the latter and a screw 28 extending through and projecting inwardly from the wall of 110 the same. Thus, the sleeve 25 and terminal piece or collar 26 carried thereby may turn around the shaft 8 as an axis, the screw 28 extending beyond the edge of the disk 27 and serving to prevent the parts from separating. The end of the flexible device A is placed opposite a notch 29 in the sleeve 25 so that the pinion *a* on the end of the shaft *b* of the flexible device A will engage a pinion *c* carried by a hollow hub *d* which is 120 revolvably mounted in the sleeve 25. The shaft 8 is extended through this hub *d* and is provided with a flat portion 80 which engages a flat portion *e* in the bore of the hub *d* to effect a driving connection between the latter and the shaft 8. The shaft 8 is also provided with a circular groove 33, and this groove is to be engaged by the hook 32 of a plate 30 which is pivoted at 31 to the head of the flexible device A. When 130

this is done a square piece 34 pivoted at 35 on the sleeve 25 is turned down on the head of the flexible device A so that its projection 36 bears against the plate 30 and prevents it 5 from becoming disengaged from the shaft 8. This construction apparently prevents the flexible device from becoming uncoupled from the sleeve 25.

The flexible device A constructed at its 10 connecting end in the manner shown in the accompanying drawings, being capable of moving in all directions without its connection with the shaft 8 ceasing, it is easy to understand that the operator holding the 15 syringe between the middle finger and the forefinger, can move it in any direction without the rotation of the shaft being impeded. This rotation will only cease at the moment when the rotation of the shaft of 20 the flexible device is arrested at the wish of the operator.

The syringe filled with liquid to be injected being connected, as just stated, to the end of the shaft of the flexible device the 25 latter being not yet set in rotation, the said syringe held between the third finger and the fore-finger which are placed on the projecting surfaces of the box 5, the operator puts the point of the needle 3 in the pre- 30 cise spot in the tissues where the anesthetic or other liquid is to be injected, without moving the hand but if necessary supporting the last two fingers of the hand against the patient's teeth in order that the operator's 35 hand may easily follow the instinctive resistant movements of the patient without the operator having to fear that the needle may move and come out of the tissues, sets the shaft of the flexible device in rotation 40 which causes rotation of the worm 7, wheel 9 and of the hub 10 and movement of the piston to force the liquid slowly and progressively into the needle and the tissues. By stopping the rotation of the shaft of the 45 flexible device at the required moment the injection is stopped.

Instead of being entirely of metal the piston 22 may be lined with asbestos for example or be made of india-rubber.

50 What he claims and desired to secure by Letters Patent is:

1. In a hypodermic syringe, the combination of a barrel, a screw threaded rod slidably but non-rotatably mounted in said barrel 55 and carrying a piston at one end operable in said barrel, a nut rotatably mounted at one end of said barrel and meshing with said rod for moving the latter and said piston longitudinally in said barrel, a flexible mem- 60 ber having a swiveled connection with said barrel, a flexible power driven rotary shaft mounted within said member, and gearing interposed between said shaft and said nut for rotating the latter, said gearing permit- 65 ting said member to swing upon its swiveled

connection with said barrel to permit said member to be maintained in parallel relation with said barrel.

2. In a hypodermic syringe, the combination of a barrel, a gear casing fixed upon one 70 end of said barrel and extending transversely of the same, a screw threaded rod slidably but non-rotatably mounted in said barrel and carrying a piston at one end operable in said barrel, a nut rotatably mounted in 75 said casing and meshing with said rod for moving the latter and said piston longitudinally in said barrel, a flexible member leading to said casing and having a swiveled connection therewith, a flexible power driven 80 rotary shaft mounted within said member, gearing mounted in said casing and between said shaft and said nut for rotating the latter, said gearing permitting said member to swing upon its swiveled connection with 85 said casing to permit said member to be maintained in parallel relation with said barrel.

3. In a hypodermic syringe, the combination of a barrel, a gear casing fixed upon one 90 end of said barrel and extending transversely of the same, a screw threaded rod slidably but non-rotatably mounted in said barrel and carrying a piston at one end operable in said barrel, a nut rotatably mounted in 95 said casing and meshing with said rod for moving the latter and said piston longitudinally in said barrel, a sleeve extending from one side of said casing at right angles to said rod and having a swivelled connec- 100 tion to said casing, a flexible member leading to said sleeve and having a detachable connection with the same, said member being arranged at right angles to said sleeve, a flexible power driven rotary shaft mounted 105 within said member, and gearing disposed in said casing and said sleeve between said shaft and said nut for rotating the latter, said gearing permitting said sleeve to turn upon its swiveled connection with said cas- 110 ing to permit said member to be maintained in parallel relation to said barrel.

4. In a hypodermic syringe, the combination of a barrel, a gear casing fixed upon one 115 end of said barrel and extending trans- versely of the same, a screw threaded rod slidably but non-rotatably mounted in said barrel and carrying a piston at one end operable in said barrel, a nut rotatably mounted in said casing and meshing with 120 said rod for moving the latter and said pis- ton longitudinally in said barrel, a sleeve ex- tending from one side of said casing at right angles to said rod and having a swiveled connection to said casing, a flexible member 125 leading to said sleeve and arranged at right angles thereto, a flexible power driven rotary shaft enclosed in said member, gearing mounted in said casing and said sleeve be- 130 tween said shaft and said nut for rotating

the latter, part of said gearing being mounted upon a shaft extending through said casting and longitudinally through said sleeve, one end of the last mentioned shaft having an annular groove therein, a hook pivoted to said flexible member and engageable with said groove for removably fastening said member to said last mentioned shaft and to

said sleeve, and means for maintaining said hook in engagement with said groove. 10

In testimony whereof he has affixed his signature, in presence of two witnesses.
